UNITED STATES PATENT OFFICE.

AUGUSTUS L. CENTER, OF WEEDSPORT, NEW YORK.

CRANK-SHAFT CONNECTION.

SPECIFICATION forming part of Letters Patent No. 374,174, dated December 6, 1887.

Application filed August 22, 1887. Serial No. 247,548. (No model.)

To all whom it may concern:

Be it known that I, AUGUSTUS L. CENTER, of Weedsport, in the county of Cayuga and State of New York, have invented a new and 5 useful Improvement in Crank-Shaft Connections for Churns, &c., which improvement is fully set forth in the following specification and shown in the accompanying drawings.

The object of my invention is to produce an 10 improved device to receive rectilinear reciprocating motion from a crank by means of a connecting-rod, the same being hereinafter fully described, and more particularly pointed out in the claims.

15 This improved reciprocating device, though adapted to various uses, is here shown in the form of a rod for a churn-dasher.

Referring to the drawings, Figure 1 is a side elevation of a churn of any suitable form with 20 my improved reciprocating rod attached to the dasher; Fig. 2, an end elevation of the same, seen in the direction indicated by arrow in Fig. 1, the crank-shaft being transversely sectioned, as on the dotted line x in Fig. 1, the 25 standards being in part broken away; and Fig. 3, a view of the connecting-rod or pitman, seen in the direction in which Fig. 2 is seen.

Referring to the parts of the device as shown, A is the body of the churn, constituting the 30 cream-chamber, which may be of any suitable form and kind.

B are standards rising from the body for the purpose of holding the crank-shaft a , which shaft is provided with an overhanging inertia 35 wheel, b , at one end and at the other with a spur-pinion, c .

d is a spur-gear held upon a stud, e , projecting from one of the standards. This gear engages the pinions and is provided with a 40 crank, f , by means of which the shaft a is rotated. As shown, the shaft is formed with two cranks turned in opposite directions to cause the reciprocating rods to alternate in their action. The reciprocating rods g are each 45 formed with an offset part, h , both of which are divided at their upper free ends into tines i , made to straddle the shaft a . The reciprocating rods, preferably made rectangular in cross-section, pass through rectangular orifices 50 k in the lid l of the churn-body, and are pro-

vided with cross-bars n of common form at their lower ends. It will be seen that the orifices k and the tines of the offset parts h form guides for the reciprocating rods, by means of which they are prevented from turning on 55 their axes and are caused to move vertically as the shaft is turned. The reciprocating rods are connected with the respective cranks of the shaft a by means of pitmen o . These pitmen are each formed with a solid head, p , having an orifice, r , to receive a pin, s , rigid in an enlarged part, t , of the reciprocating rods. A strap, u , secured to the reciprocating rods, holds the inner end of the pin. These pitmen are formed with orifices v , in which to receive 60 the respective crank-pins, and are further divided longitudinally nearly their whole length in the plane of the axes of the openings v and r . On account of this division the divided parts may be sprung apart, as indicated by 65 dotted lines in Fig. 3, to put the pitmen onto the crank-pins. A loop, a' , pivoted at b' to one of said divided parts of each pitman, so as to turn thereon, serves to hold the parts 70 firmly together when placed upon the cranks. 75 The inner surfaces of the tines i are faced with pads e' of soft yielding material—such as leather, thick cloth, or india-rubber—to bear more easily against the shaft as the reciprocating rods are pushed and pulled toward one 80 side or the other by the action of the pitmen as the cranks are turned.

What I claim as my invention is—

1. A reciprocating rod formed with an enlarged part, t , and an offset part divided at its 85 free end, in combination with a pin rigid in said enlarged part, a rotary crank-shaft and crank, and a pitman joining said crank and pin.

2. A reciprocating rod formed with an enlarged part, t , and a divided offset part, in combination with a pin rigid in said enlarged part, a rotary crank-shaft and crank, and a pitman joining said crank and pin, the tines of said divided offset part being padded, for 90 the purpose set forth.

AUGUSTUS L. CENTER.
